UNITED STATES PATENT OFFICE.

HARRY NEWBOLD, OF LONDON, ENGLAND.

EYEGLASSES.

1,098,831.

Specification of Letters Patent. Patented June 2, 1914.

Application filed September 23, 1910. Serial No. 583,401.

To all whom it may concern:

Be it known that I, HARRY NEWBOLD, a subject of the King of Great Britain, residing at 46 and 48 Goswell road, in the county of London, England, have invented certain new and useful Improvements in Eyeglasses, of which the following is a specification.

My invention relates to improvements in eyeglasses and to that type thereof in which the guards are pivotally connected to the mounting and provided with springs for holding them in engagement with the nose of the wearer.

The object of my invention is to provide a mounting wherein the guards are operated by single actuating means whereby the pressure on both sides of the nose is equalized.

Other objects of my invention are to provide means whereby the nose guards may adjust themselves to the wearer's nose in two directions; to provide means whereby the nose guards will tend to increase their grip on the nose when moved in the direction of displacement; and to provide a one piece blank for manufacture of the bridge and lense fittings.

I attain these objects by the construction illustrated in the accompanying drawing in which:

Figure 1, is a rear elevation of a pair of eyeglasses having my improvements applied thereon. Fig. 2, is a sectional plan view thereof. Fig. 3, shows a one piece blank for the lens fittings and bridge members. Fig. 4, shows in perspective the blank bent to form, nose guard and lever attached. Fig. 5, is a perspective view of a modified nose guard, having bearings disposed in two planes. Fig. 6, shows a plan view of the modified nose guard pivoted on the inner edge as illustrated in Figs. I and V. Figs. 7 and 8, show the plan view and elevation of a modified form of mounting with rigid bridge members.

Similar figures refer to similar parts throughout the several views.

Referring to the drawings: The two lenses *a*, *a*, are connected by means of two bars or bridge members, *b* and *c*, which slide horizontally on each other through perforated shoulders *b'* and *c'*, the shoulder *b'* being secured to the bar *b* and shoulder *c'* to the bar *c*. A spiral spring *e* is coiled around the two bars forming the bridge piece and is held between the two shoulders *b'* and *c'*. The shoulders *b'* and *c'* may either be rigidly

attached to the bars *b* and *c* or may be loose thereon. Lens fitting *f* integral with the bar *b* and a corresponding fitting *g* integral with the bar *c* are formed at their lower ends with forked connections *h* to which the lenses *a* are attached in the usual well known manner. Upright spindles or arbors *i*, *i*, which are mounted in bearings *j* and *k* upon the fittings *f* and *g* have lower inwardly extending cranked ends *l*, *l*, which pivotally carry the guards *m*, *m*, and upper outwardly extending cranked ends *n*, *n*, which constitute finger pieces for operating the spindles. These finger pieces *n*, *n*, pass through holes *o*, *p*, provided respectively in the bars *b* and *c* and through corresponding slots *o'*, *p'* in the bars *c* and *b*, the said holes *o* and *p* being positioned outside the shoulders *c'* and *b'*. The forked connections *h*, the fitting *g* or *f*, and the bar member *b* or *c* are preferably made from a one piece blank as shown in Fig. 3 and bent to shape as shown in Fig. 4, the lower bearing *j* being attached to the blank.

The operation of the parts is as follows: When the finger pieces *n*, *n*, which are normally pressed by the springs *e* toward their corresponding lenses as shown in the drawing, are manipulated by the wearer so as to be drawn toward one another, the bar members *b* and *c* are extended, compressing the spiral spring *e* and increasing the distance between the pupillary centers of the lenses, the spindles *i*, *i* are rotated at the same time in their bearing *k* and *j* causing the guard members *m*, *m*, to recede from each other. This rotary movement is communicated to the spindles *i*, *i*, through the finger pieces *n*, *n*, contacting with the holes *o* and *p* in the bar members *b* and *c*, and sliding in the slots *o'* and *p'*. The extension of the bar members and the recession of the guards permits the eyeglasses to be placed upon the nose of the wearer. On releasing the pressure on the finger pieces *n*, *n*, the bridge members contract and the guards close together and form the necessary grip on the nose, this being effected by the spring *e* forcing the finger pieces toward their corresponding lenses and rotating the nose guard spindles.

In Figs. 5 and 6 I have shown a modification of the guards *m*, *m* in which the horizontal bearing shoulder is made separate from the back of the guard, in the form of a spider member *r* provided with vertical integral pintles which engage the bearings *s*

on the guards *m*, *m* and allow the guards to rotate in a vertical plane. The guards are thus permitted to adjust themselves to the irregularities of the nose in both the horizontal and the vertical planes. By placing the pivot bearings *s* on the inner edge of the guards as shown in Fig. 6, the free edges of the guards will catch the flesh of the nose when the eyeglasses are pulled away from the face of the wearer and the outer edges turn toward each other about the bearings *s* and increase their grip on the nose.

In Figs. 7 and 8 I have shown a modification wherein the bars *b* and *c* are combined in one piece and the lenses *a*, *a* rigidly connected. The holes *o* and *p* and the slots *o'* and *p'* are omitted and the finger pieces *n*, *n*, are not brought into contact with the bar members or bridge, but pass freely there-over and engage the ends of the spring *e* thereon. In this construction the pupillary distance between the lenses remains fixed and the glasses are adjusted by the recession of the guards *m*, *m*, alone as previously described.

In Fig. 3 I have shown a method of cutting out a blank from a flat sheet which can be bent to shape to form the forked members *h*, the fittings *g*, *f*, and the bar members *b*, *c*, as shown in Fig. 4.

Eyeglass fittings made as above described possess a number of advantages in practice. For example, when the finger pieces are pressed toward each other as above described, the guards open out by the action of a single spring so that unequal pressure upon the two guards can not occur as is possible where each guard is fitted with an independent spring. The double offset bearings of the nose guards permit them to adjust themselves to uneven contours in both directions, and provide an automatic tightening device to resist unintentional displacement of the eyeglasses, while the one piece blank facilitates and cheapens the manufacture of the fittings.

Having now described my invention, what I claim as new and desire to secure by Letters Patent is:

50 1. In an eyeglass mounting the combination of a pair of lenses connected by a bridge, pivotally mounted nose clamp levers, and a single actuating means between and adapted to actuate both nose clamp levers.

55 2. In an eyeglass mounting the combination of a pair of lenses connected by a bridge, pivotally mounted nose clamp levers, and a spring on the bridge between and adapted to operate both of the nose clamp levers.

60 3. In an eyeglass mounting the combination of a pair of lenses connected by a bridge, pivotally mounted nose clamp levers, and a spiral spring between and adapted to operate both of said nose clamp levers.

4. In an eyeglass mounting the combination of a pair of lenses connected by a bridge, pivotally mounted nose clamp levers and a spiral spring disposed on the bridge between the nose clamp levers and adapted to actuate the nose clamp levers simultaneously.

5. In an eyeglass mounting the combination of a pair of lenses connected by a bridge, pivotally mounted nose clamp levers, and actuating means, disposed between the nose clamp levers, the opposite ends of which contact with and actuate the nose clamp levers.

6. In an eyeglass mounting the combination of a pair of lenses connected by a bridge, pivotally mounted nose clamp levers, the outer ends of which are cranked to form finger pieces, nose guards pivoted adjacent the inner ends of the nose clamp levers, and actuating means on the bridge between the finger pieces adapted to operate the nose clamp levers.

7. In an eyeglass mounting the combination of a pair of lenses connected by a bridge, pivotally mounted nose clamp levers, slideable shoulders on the bridge and actuating means between said shoulders adapted to push them apart and actuate the nose clamp levers.

8. In an eyeglass mounting the combination of a slideable bridge, lens fittings connected thereto, pivoted guards and means for simultaneously adjusting the distance between the lens fittings and the angle of the guards.

9. In an eyeglass mounting the combination of a pair of lenses connected by slideable bridge members, rotatably mounted spindles having their upper ends cranked outwardly and operatively engaging the bridge members and means for actuating the upper cranked ends of the spindles and horizontally adjusting the pupillary distance between the lenses.

10. In an eyeglass mounting the combination of slideable bridge members, lens fittings connected thereto, guards mounted on the lower cranked ends of spindles held in bearings on the lens connections the upper ends of which are cranked to form finger pieces and engage the bridge members and actuating means disposed between the finger pieces and adapted to actuate the said spindles and bridge members.

11. In an eyeglass mounting the combination of a pair of lenses connected by slideable bridge members, pivotally supported cranked levers, the upper ends of which form finger pieces and operatively engage the bridge members, a nose guard mounted on the lower cranked ends of said levers and actuating means adapted to actuate said bridge members and cranked levers, substantially as shown and described.

12. In an eyeglass mounting the combination of a pair of lenses connected by slidable bridge members, bearing lens engaging means, nose clamp levers pivoted thereon, the upper ends of which levers are cranked to form finger pieces to operatively engage the bridge members, a bearing spider having oppositely disposed bearings pivoted on the lower cranked arms of the levers, a nose 65 guard pivoted on the spider and actuating means disposed between the finger pieces adapted to actuate the nose clamp levers and the bridge members substantially as shown and described.
13. In an eyeglass mounting the combination of a pair of lenses connected by a bridge, and lens engaging members, vertical nose clamp levers pivoted to the lens connecting means and having their upper ends cranked outwardly to form finger pieces, and the lower ends cranked inwardly to form nose guard bearing arms, and nose 70 guards pivoted on the lower cranked arms, substantially as shown and described.
14. In an eyeglass mounting the combination of a pair of lenses connected by a bridge, and lens engaging means and cranked spindles pivoted vertically to the lens connections, having outwardly extending finger pieces and inwardly extending arms, nose guards on the inwardly extending arms, and means for rocking or rotating the guards simultaneously in two normal planes, substantially as shown and described.
15. In an eyeglass mounting the combination of a pair of lenses connected by a bridge, having lens engaging members, vertical cranked levers pivoted to the lens connections and having outwardly extending finger pieces and inwardly extending arms, a nose guard and a spider bearing connecting said guard and inwardly extending arm having a hub pivoted on the lever arm and integral normally disposed pintles engaging 90 bearings on the guards.
16. In an eyeglass mounting the combination of a pair of lenses connected by slid- 105 able bridge members, vertical spindles mounted in bearings thereon, the upper ends cranked outwardly and extending through recesses in the bridge members, and the lower ends cranked inwardly and pivotally supporting nose guards, and centrally disposed actuating means on the bridge adapted to actuate the upper cranked ends of the spindles and simultaneously adjust the pupillary distance of the lenses and the angle of the nose guards.
17. As an article of manufacture, a blank 110 for an eyeglass bridge and lens attachment comprising a fitting having forked lens connections, a projection forming a bridge sec- 115 tion, and an extension on the fitting providing a bearing for the nose clamp lever.
18. As an article of manufacture, a nose 120 guard for eyeglasses comprising a nose bearing portion and a bearing spider having an inwardly extending perforated hub and upwardly and downwardly extending pintles engaging pivot bearings on the nose bearing portions, substantially as shown and described.
19. As an article of manufacture, a nose 125 bearing portion and a spider having bearing members disposed in two planes, those in the vertical plane engaging pivot members on the back inner edge of the bearing portion and the horizontal member adapted to 130 engage an eyeglass nose clamp lever, substantially as shown and described.
20. As an article of manufacture, a rocking guard for eyeglasses and spectacles comprising a nose bearing portion and a bearing spider, the said spider having bearing members disposed in two planes substantially normal to each other, the inwardly extending bearing being a perforated hub 135 adapted to engage a cranked nose clamp lever, and the other bearing being upwardly and downwardly extending pintles connected to the rear inner edge of the nose bearing portion, substantially as shown and described.
21. As an article of manufacture, a spider bearing for nose guards of glasses, having an inwardly extending hub adapted to pivotally engage a nose clamp lever, and integral pintles normally disposed to said 140 hub and adapted to pivotally engage bearings on a nose guard.
22. In an eyeglass mounting the combination of a vertical nose clamp spindle having its upper end cranked outwardly to form 145 a finger piece and its lower end cranked inwardly to act as a nose guard support, and a bearing spider having an inwardly extending hub pivoted on the lower cranked end of the lever and integral pintles normally disposed to the hub and rotatably contacting with the rear inner edge of the nose guard, substantially as shown and described.
23. In an ophthalmic mounting, the combination with a clip, of a vertical support formed integral therewith and projecting therefrom, a bearing and a bridge carried by the support and a second bearing aligned with the first and disposed adjacent the clip.
